UNITED STATES PATENT OFFICE.

JULIUS F. MEDVECKY, OF SAN FRANCISCO, CALIFORNIA.

PARACHUTE ATTACHMENT FOR AEROPLANES.

1,116,312.

Specification of Letters Patent.

Patented Nov. 3, 1914.

Application filed April 21, 1913. Serial No. 762,615

To all whom it may concern:

Be it known that I, JULIUS F. MEDVECKY, a citizen of the United States, residing in the city and county of San Francisco and State of California, have invented new and useful Improvements in Parachutes Attachments for Aeroplanes, of which the following is a specification.

This invention relates to a parachute attachment for aeroplanes.

It is the object of this invention to provide a parachute attachment for aeroplanes which is so constructed and arranged as to automatically open when the aeroplane is accidentally tipped to an abnormal angle, and which will serve to right the aeroplane and prevent its falling at a dangerous speed in event of disability.

A further object is to provide a parachute attachment for aeroplanes which is simple in construction and efficient and reliable in operation.

Other objects will appear hereinafter.

The invention primarily resides in an umbrella-shaped parachute pivotally connected a short distance to one side of the center of gravity of an aeroplane, and adapted to normally lie in a horizontal position, and means for automatically distending the parachute when the aeroplane is disposed at a predetermined angle, and means by which the opening of the parachute will operate to right the machine.

The invention further consists of the parts and the construction and combination of parts as hereinafter more fully described and claimed, having reference to the accompanying drawings, in which—

Figure 1 is a plan view showing the invention as applied to an aeroplane. Fig. 2 is a side elevation of same showing the parachute in its normal horizontal position in full lines, and in the open position in dotted lines. Fig. 3 is a detail longitudinal section of the parachute, showing the mechanism for automatically opening the same and illustrating in dotted lines the manner of opening the parachute and righting the aeroplane frame thereby.

In the drawings A represents an aeroplane which may be of any suitable type or construction. For the purpose of illustration let it be assumed that the center of gravity of the aeroplane is situated at the point B. The present invention resides in pivotally mounting a frame 2 at one side of

the center of gravity B, a short distance therefrom; in this case the frame 2 being pivoted at 3 forward of the point of gravity B. The frame 2 is designed to normally extend in a horizontal direction and rest on a projection 5 on the side of the aeroplane body.

Attached to the frame 2 is a rod 7, carrying a series of spreading ribs 8 on its outer end, to which are attached brace ribs 9, connected to a sleeve 10, slidable on the rod 7. The spreading ribs 8 are covered with a suitable fabric 8' to form the parachute. When the parachute is in its normal full position it will be disposed horizontally, as shown in Figs. 2 and 3, with its outer end extending into a circular plate or shield 11, having an annular flange 12 on its outer periphery, adapted to engage the outer ends of the ribs 8 of the parachute to retain the latter in its folded position. The plate 11 has a slight reciprocal movement on the rod 7, and is normally held in its innermost position by means of a helical spring 13, wound on the rod 7 and bearing between the rear of the plate 11 and a shoulder on the rod 7. The shield 11 serves to prevent air from entering the parachute tending to open same when the aeroplane is in motion.

Mounted on the rod 7 at a convenient point is a standard or frame 14, on which a lever 15 is pivotally mounted; the end of the lever 15 is slotted; 16 at 16, and engages a pin 17 on a sleeve 10', which normally bears against the sleeve 10 to which the brace ribs 9 are connected. The other end of the lever 15 is provided with a weight 18.

In the operation of the invention when the aeroplane is accidentally tilted at an abnormal angle, the weight 18 will operate to rock the lever 15 and move the sleeves 10 and 10' rearwardly on the rod 7, thereby causing the parachute ribs 8 to spread; the ends of the ribs riding over the inclined inner periphery of the flange 12 and thereby moving the plate 11 rearwardly sufficiently far to release the ends of the ribs 8 therefrom. The moment the ribs pass beyond the outer edge of the plate 11, air will be allowed to enter the parachute and thereby operate to open the latter in the usual manner. As the ribs 8 are spread by reason of the pressure of the air thereunder, the outer edge of the parachute is brought to bear upon the frame of the aeroplane at a point

rearward of the center of gravity B, as indicated in dotted lines in Fig. 3. When this occurs, the parachute will be sufficiently opened to cause an upward pull to be exerted 5 on its pivotal point 3, forward of the center of gravity B. The upward pull at the point 10 2 on one side of the center of gravity B, and the downward pressure occasioned by the edge of the parachute on the opposite side 15 of the center of gravity B, tends to restore the aeroplane to its normal position, in which position it is maintained by reason of the center of gravity B being rearward of the point of suspension 3. The parachute 20 15 will be caused to move to its extended or open position, as indicated in dotted lines in Fig. 2, in which position the rock frame 2 will be disposed vertically against a stop 19, arranged at a convenient point on the 25 aeroplane body. This stop 19 serves to prevent the rear portion of the aeroplane being rocked downward in relation to the point of suspension 3 by its normal center of gravity B.

Having thus described my invention, what I claim and desire to secure by Letters Patent is:

1. In combination with an aeroplane, a 30 parachute having a normally horizontally disposed handle which overlies the center of gravity of the aeroplane and has one end pivoted to the latter at a point to one side of the center of gravity, means to hold the 35 parachute in collapsed position, and means confined within and surrounded by the fabric of the parachute and located on the opposite side of the center of gravity and connected to said handle for automatically releasing the holding means and to move 40 with the parachute to a vertical position on the first named side of the center of gravity.

2. In combination with an aeroplane, a

parachute having a handle connected to the aeroplane, means to hold the parachute collapsed, and means connected to the handle 45 and confined within and surrounded by the fabric of the aeroplane for automatically releasing the holding means when the aeroplane tilts.

3. In combination with an aeroplane and 50 a parachute having a handle connected thereto, a spring pressed shield on the handle to engage the ribs of the parachute and hold same collapsed, a sleeve slidable on the 55 rod, said sleeve being located between the shield and the connecting sleeve of the parachute ribs, a lever having one end weighted and its opposite end connected to the sleeve, said lever being also mounted between the shield and the connecting sleeve of the 60 parachute ribs and being confined within and surrounded by the fabric of the parachute, and means to pivotally connect said lever between its ends to said handle.

4. In combination with an aeroplane and 65 a parachute connected thereto, means to hold the parachute collapsed, and means confined within and surrounded by the parachute for automatically releasing the holding means 70 when the aeroplane tilts.

5. In combination with an aeroplane, and 75 a parachute connected thereto, means to hold the parachute collapsed, and means in connection and movable with the parachute to automatically release said holding means when the parachute tilts.

In testimony whereof I have hereunto set my hand in the presence of two subscribing witnesses.

JULIUS F. MEDVECZKY.
